United States Patent Office

Des. 183,884
Patented Nov. 11, 1958

183,884

AQUARIUM FILTER OR THE LIKE

Abby Halpert, Brooklyn, N. Y.

Application March 19, 1957, Serial No. 45,321

Term of patent 14 years

(Cl. D91—2)

Fig. 1 is a perspective view of an aquarium filter or the like showing my new design;

Fig. 2 is a sectional view along line 2—2 of Fig. 1.

Fig. 3 is an enlarged fragmentary sectional view along line 3—3 of Fig. 1 with portions thereof omitted for convenience of illustration.

I claim:

The ornamental design for an aquarium filter or the like, as shown.
